J. A. JOURDIN

COLLAPSIBLE OR KNOCKDOWN CONTAINER

Filed April 27, 1923

INVENTOR
JOSEPH A. JOURDIN.

BY *Feekeston Haughway*
ATTYS.

UNITED STATES PATENT OFFICE.

JOSEPH ALFRED JOURDIN, OF OTTAWA, ONTARIO, CANADA.

COLLAPSIBLE OR KNOCKDOWN CONTAINER.

Application filed April 27, 1923. Serial No. 635,097.

To all whom it may concern:

Be it known that I, JOSEPH ALFRED JOURDIN, a subject of the King of Great Britain, and resident of Ottawa, in the Province of Ontario and Dominion of Canada, have invented certain new and useful Improvements in Collapsible or Knockdown Containers, of which the following is a specification.

10 This invention relates to improvements in collapsible or knock-down containers and the objects of the invention are to provide a container in the form of cheese boxes, barrels, or, in fact, in any suitable form that 15 can be readily collapsed and thus easily and economically transported in a limited space, thereby materially reducing freight charges.

Further objects are to provide a container of this kind that cannot be tampered with.

20 Still further objects are to provide a container formed with laced staves and interchangeable covers, that can be completely collapsed or built up at very short notice and that can be economically manufactured 25 and placed on the market in large quantities at low cost.

With the foregoing and other objects in view, the invention consists essentially of a collapsible container formed of a plurality 30 of sections placed together in such manner that the lacing means are entirely concealed, thus providing a container of this character that cannot be easily tampered with.

Referring now to the drawings, in which 35 like characters of reference indicate corresponding parts in each figure,

Figure 1 is a perspective view of an embodiment of my device as a whole, in the form of a container.

40 Figure 2 is a cross sectional view with the cover removed and showing the lacing means concealed within the sections of the container.

Figure 3 is a vertical section through the 45 container.

Figure 4 is a longitudinal section of the cover, showing the assembling or lacing of the sections comprising it.

In the drawings, A designates the device 50 as a whole of any suitable material, size or form and here shown as constructed of wood in the form of a container adapted to hold cheese or the like and comprising, in detail, a plurality of sections or staves 10 laced 55 or strung together on flexible connecting means in the shape of wires 11 designed to

extend through said sections by means of suitable holes bored therein and the loose ends of which are drawn together inwardly at 12 and secured with any suitable instrument in slots 13 on the inside of the container. In this way, the strung or laced sections are when built up, as shown in Figure 1, designed to form the body 14 of the container while in knock-down position they 60 will lie flat, thus taking up comparatively little space in transit.

15 and 16 are top and bottom removable cover members for the container and are formed in sections 17 suitably bored at 18 70 to be similarly laced together by means of wires 19.

20 are fastening hooks of any well known construction adapted to hold the top and bottom covers in position. If desired, however, these hooks may be dispensed with and the wires 11 in the container instead of being confined in the slots 13 can readily be brought upwards inside the container to extend through suitable openings in the 80 cover and then bent to hold the cover in position just as effectually as if held by the hooks here illustrated.

25 My container may also be provided with ventilating means of any well known kind, if required.

From the foregoing, it will be observed that I have provided a simply constructed and practical means of manufacturing knock-down or collapsible containers of all 90 kinds, in which the feature is the lacing of the sections composing the container together by stringing them on wires. Another feature is that the sections being so strung or laced and the loose ends of the wires concealed within the container, the means of connecting and building up the device are 95 entirely concealed and consequently not easily tampered with nor are they affected, by exposure, to rust or otherwise.

100 As many changes could be made in the above construction and many apparently widely different embodiments of my invention within the scope of the claim, constructed without departing from the spirit 105 or scope thereof, it is intended that all matter contained in the accompanying specifications and drawings shall be interpreted as illustrative and not in a limiting sense.

110 What I claim as my invention is:
A collapsible container or the like comprising a plurality of sections suitably bored

and provided with flexible securing means through said bores adapted to lace the members together to form a body portion, top and bottom cover means for said body portion comprising sections similarly bored and provided with similar lacing means there-through, the loose ends of the lacing means

being carried through the cover means and then bent to hold the covers in position.

In witness whereof I have hereunto set ¹⁰ my hand in the presence of a witness.

JOSEPH ALFRED JOURDIN.

Witness:

W. T. CUFFE QUIN.
